UNITED STATES PATENT OFFICE.

JOHN H. WAY, OF HASTINGS, NEBRASKA.

DESIGN FOR A CHIMNEY-PROTECTOR.

SPECIFICATION forming part of Design No. 29,498, dated October 18, 1898.

Application filed September 21, 1898. Serial No. 691,560. Term of patent 14 years.

To all whom it may concern:

Be it known that I, JOHN H. WAY, a citizen of the United States, residing at Hastings, in the county of Adams and State of Nebraska, 5 have invented and produced a new and original Design for Chimney-Protectors; and I do hereby declare the following to be a full, clear, and exact description of the same, reference being had to the accompanying drawings, forming a part thereof.

In the accompanying drawings, Figure 1 represents a perspective view of the chimney-protector embodying my design, and Fig. 2 is a vertical longitudinal section through the 5 same.

The leading feature of my design consists of a vertical body portion and a downwardly and outwardly flaring portion, which surrounds the vertical portion and extends from 5 the same in opposite directions.

A in the drawings represents the vertical body portion of the protector, which is rectangular in shape and of a suitable length.

B represents the outwardly and downwardly extending flaring portion which surrounds the vertical portion and extends from the same in opposite directions. 25

Having now described my invention, what I claim as new, and desire to secure by Letters Patent, is—

The design for a chimney-protector, substantially as herein shown and described. 30

In testimony whereof I hereunto affix my signature in presence of two witnesses.

JOHN H. WAY.
